CLAIM

The ornamental design for a lamp holder attachment for headgear, as shown and described.

DESCRIPTION

FIG. 1 is a perspective view of a new design for a lamp holder attachment for headgear suitable for mounting on a hard hat, helmet, or the like;

FIG. 2 is a front view thereof in which the slot for holding a lamp can be seen;

FIG. 3 is a side view thereof;

FIG. 4 is a bottom view thereof;

FIG. 5 is a back view thereof;

FIG. 6 is a top view thereof; and,

FIG. 7 is a side view of the lamp holder attachment for headgear on a welding helmet.

The dashed broken lines depict portions of the article and form no part of the claimed design. The broken line in FIG. 7 is depicted for environmental purposes only and forms no part of the claimed design.

1 Claim, 4 Drawing Sheets
